UNITED STATES PATENT OFFICE.

MATHIAS ANTON KOHN, OF MILWAUKEE, WISCONSIN.

GARBAGE INCINERATOR.

Application filed October 12, 1922. Serial No. 594,625.

To all whom it may concern:

Be it known that I, MATHIAS ANTON KOHN, a citizen of the United States, and resident of Milwaukee, in the county of Milwaukee and State of Wisconsin, have invented certain new and useful Improvements in Garbage Incinerators; and I do hereby declare that the following is a full, clear, and exact description thereof.

This invention relates to garbage incinerators, and is particularly directed to an incinerator in which a burner is employed and is mounted below the charge of garbage, and, in general, this invention is an improvement over my former invention, upon which I secured a patent February 15, 1921, No. 1,368,809, disclosing a garbage incinerator. The present invention has the same general objects as those of my former invention.

In garbage burners as heretofore constructed, considerable difficulty has been experienced in the clogging of the burner and associated parts with the consequent difficulties thereby entailed. A further difficulty in properly consuming the charge in the former types of incinerators is due to the fact that the flames and heated products of combustion cannot penetrate the charge freely, but must burn the charge gradually from the outside inwardly. This, under the best conditions, is a serious handicap to the efficiency of the operation of the incinerator, and when it is considered that the garbage is frequently moist and in a soggy condition, it becomes at once apparent that the process of incineration, under these conditions, is extremely slow.

It is to overcome these difficulties that the present invention is designed, and objects of this invention are to provide a garbage incinerator which is so constructed that the flames and heated products of combustion are caused to pass freely through the charge, thereby burning the charge both from the outside inwardly and from the inside outwardly, thereby hastening the incineration and providing a more efficient operation.

Further objects are to provide a garbage incinerator, in which the burner is protected and guarded, thereby avoiding clogging of the burner, in which a flame distributor and conductor is provided, and is removably carried within the incinerator, and in which a removable grate is provided.

An embodiment of this invention is shown in the accompanying drawings, in which:—

Figure 1 is a vertical elevation of the incinerator, and

Figure 2, is a detail of the upper support for the flame conveyor.

Referring more particularly to the drawings, it will be seen that the incinerator comprises an outer shell 1 carried upon a closed base 2 and provided with a bottom door 3, a flue pipe 4 and a garbage receiver 5, the garbage receiver being of the type adapted to automatically close after the garbage has been passed through it.

With the shell 1 a plurality of inwardly projecting lugs 6 are mounted and supported a perforated colander 7 which is provided adjacent its lower portion with an inwardly projecting flange or rib 8. A hopper 9 is supported from the flange 8 and is of a truncated conical shape having a restricted open bottom portion. A removable, relatively coarse grate 10 is positioned within the hopper 9 and seats within the hopper adjacent its lower portion. A burner 11 is positioned directly beneath the lower portion of the hopper 9 and may be supplied from the gas main 12 through a control valve 13. This burner is a tilting burner similar to that previously described in my above noted patent and is adapted to tilt when the shaft 14 is rocked, a suitable weight 15 being provided for restoring the burner to its horizontal position.

The flame distributor consists of an upwardly tapering tubular member 16 having a series of apertures 17 along its extent and having a closed upper portion 18 and an open bottom portion 19. This flame distributor may conveniently be formed of two half sections secured by suitable screws or bolts, as indicated at 20. This lower portion is provided with a plurality of outwardly extending feet 21 which seat upon portions of the grate 10 to support and steady the lower portion of such distributor. The upper portion of said distributor is provided with a perforated ear 22 which is adapted to be loosely positioned upon a hook 23 carried by the top 24 of the incinerator.

It is to be particularly noted that the incinerator is so organized that the flames and heated products of combustion pass freely through the grate and into the charge and

upwardly through the flame distributor and into the interior of the charge. In this manner a very large portion of the charge is directly exposed to the action of the flames and the incineration is thereby hastened. It is also to be noted that the perforated colander is spaced from the shell 1 of the incinerator. The fumes and gases may pass both upwardly from the charge and outwardly into the space between the colander and the shell, thereby providing for the rapid destruction of the charge.

I claim:

1. A garbage incinerator comprising an outer casing, a perforated colander mounted therein and spaced from such casing, a tapered hopper carried by said colander, a grate removably carried by said tapered hopper, a burner mounted below said grate, a tubular flame distributor seated upon said grate and extending upwardly therefrom and having a plurality of apertures through its walls, and means for engaging and steadyng the upper portion of said distributor.

2. A garbage incinerator comprising an outer casing provided with a top, a perfo-

rated colander mounted therein and spaced from such casing, a tapered hopper carried by said colander, a grate positioned adjacent the lower end of said hopper, a burner mounted below said grate, a tubular apertured flame-distributor extending upwardly from adjacent said grate, and interlocking means carried by said top and the upper end of said flame-distributor.

3. A garbage incinerator comprising an outer casing, a perforated colander mounted therein and spaced from such casing, a tapered hopper carried by said colander, a grate mounted below said tapered hopper, a burner mounted below said grate, a tubular apertured flame-distributor seated upon said grate and extending upwardly therefrom and terminating in an apertured ear, and a hook carried by the upper end of such casing and detachably engaging said apertured ear.

In testimony that I claim the foregoing I have hereunto set my hand at Milwaukee, in the county of Milwaukee and State of Wisconsin.

MATHIAS ANTON KOHN.
